APPARATUS FOR MAKING AND SECURING
BAG HANDLES

Roderick S. Clancy, Los Angeles, Calif.

Application April 10, 1940, Serial No. 328,883

13 Claims.

(Cl. 93—1)

My invention relates to paper bag handles and method and apparatus for fastening same, and its objects are to produce a new and improved bag handle formed from a double layer, or two layers of paper, capable of being stapled to the mouth portion of a bag; to stamp out from a roll of double thickness of paper a plurality of handles in gang formation; to advance and secure each of said handles to the mouth of a paper bag and to effect a closure of the same; to permit each of said handles readily to be torn and separated from the gang; to form a hand hold in each of said handles for the effective carrying of a loaded paper bag and at the same time affording a guard and protection for the fingers of the carrier; to arrange the operative parts of my improved apparatus in close sequential order and preserve the proper adjustment thereof, and in general to simplify and render more effective the operation of the several parts of said apparatus. Other objects and novel inventive concepts will appear from the drawings and as hereinafter more particularly set forth and described.

At the present time, there exists a great need, where paper bags are used for containers in the retail trade, for an efficient apparatus, not only for closing the mouths of paper bags, but also for providing a handle for the customer by which he can carry the bag without injury to his fingers. The ordinary paper bag, in which groceries, drygoods, hardware or other commodities are dispensed to the trade, is usually left open, or only partially closed, with the result that constant care has to be exercised to prevent the escape of its contents, and to prevent its being broken open. Also no handhold is provided upon the bag itself whereby the same can be readily carried from place to place. Through the use of my invention, however, anyone is enabled to obviate all of these objections in a manner which I believe to be novel in the art.

Attention is hereby directed to the accompanying drawings illustrating a preferred form of my invention, in which similar numerals of designation refer to similar parts throughout the several views, and in which—

Figure 1 is a view in perspective of my improved apparatus, showing the roll of double thicknesses of paper, the die for stamping therefrom the bag handles and the stapling machine and adjacent, mechanism for closing the mouth of the bag and attaching the bag handle thereto;

Fig. 2 is a view in perspective, showing one of the handles attached to a bag;

Fig. 3 is a side elevation, partly in section of the stapling machine and adjacent parts;

Fig. 4 is a plan view of the handles in gang formation, the stapling machine being shown removed for the purpose of better illustration;

Fig. 5 is an end view on line 5—5 of Fig. 3 of the parts of the structure shown in Fig. 4, looking in the direction of the arrows;

Fig. 6 is a view of a modification of the distending fingers for holding open the layers of the handle for the insertion therein and the stapling thereto of the top of the bag;

Figs. 7 and 8 are views of modifications of my improved bag handles, arranged in gang formation, each handle being in one piece, the two layers of paper being connected at the top of the handle.

Referring to the drawings, upon a base 7, which may be a box, bench or table and of any suitable material, I mount at one end thereof the paper roll 8, the axle 9 of which is journaled in bearings 10 in the brackets 11 secured to the end of the base 7. This roll is made up of two layers of paper A and B wound thereon, and is arranged so that such double layer may readily be drawn therefrom, the roller 12 serving as a friction means to hold in place the layers of paper upon the rolls 8, and to prevent the same from running wild or from being too rapidly drawn therefrom. The roller 12 is mounted upon the upper ends of the arms 13, the lower ends thereof being pivotally mounted upon pins 14 secured to each of the sides of the base 7. To ensure the frictional contact of the roller 12 with the outer layers of paper of the roll 8, I preferably supply each of said arms 13, with springs 15 affixed thereto and to the pins 14 as shown.

After being unwound from the roll 8, the lower layer of the double thickness of paper contacts the table 16 formed by the upper face of the base 7, and both thicknesses of paper resting flatly upon the rear surface of said table are free to be pulled over the said surface toward the front of said table, and to pass under the die 17 which is of the usual form of construction, and which is provided with a knife or cutting plate for cutting out of the said double thickness of paper in the shape shown in Fig. 4 the paper handles 18. As shown in Fig. 1, the die is hingedly mounted upon the base 7, by means of feet 19 integral with the casing of said die, which feet are attached to arms 20 pivotally connected with two ears 21 secured to the base 7. Only one of these arms 20 and connection is shown in Fig. 1, the construction being similar on the opposite side of

said die. Normally, in conformance with well-known forms of construction, the said arms 20 are held by a spring in raised position, which spring may be incorporated within said pivotal connection, or take any other common recognized form.

Firmly affixed to the said die 11 and in close contact with the face thereof, is the double stapling machine 22, which is of any form heretofore usually employed in the art, and which is rigidly connected with the die 11 so as to move downwardly or upwardly therewith upon its hinged attachment aforesaid to the base 7; the knob 23 serving, when struck with the hand, as a manual means for actuating the die 11 to cut out the form of handle 18, and at the same time to affix the staples in attaching a handle to a bag in the manner hereinafter described.

For the purpose of holding open the ends of the two layers of paper A and B, as they are presented to the front of my apparatus, I supply the resilient fingers 24, which serve to hold said layers apart sufficiently to permit top edges of the bag 25 to be inserted therebetween, and to allow both bag and handle to be stapled together. These fingers 24 are secured at their outer ends to the table 16, and are of such size and construction as to ensure and maintain ample space between layers A and B for the purpose aforesaid, although yielding sufficiently to permit close stapling of said layers to the top of the bag. If desired, such fingers may be constructed as shown in Fig. 6, in which case, the fingers are held at an angle with yielding tension, and are forced flat as the stapler descends and affixes the staples; the counter weight 26 serving normally to hold the finger 24 in the desired angular position.

In Fig. 4 is illustrated a preferred form of my improved paper bag handle 18, here shown in series or gang procession. Each handle 18 is preferably formed with rounded edges 27, and a slot 28 perforated through part of the division line between handles, said division line otherwise being weakened to permit tearing the handles apart. Each handle is also given by the knife of the die the cuts 29, perforations 30, and scoring 31, forming when pressed out the tabs 32. While I prefer to construct a file of detachable handles as shown in Fig. 4, this form may be changed, and the modifications shown in Figs. 7 or 8 adopted, in which case each blank is formed in one piece of paper which can be folded to present a connected handle at the top, in place of the two separate layers of paper.

The bags 25 may be of any well known form in commercial use for dispensing goods. To accomplish the best results, however, I prefer to use a bag with a flap 33, which can be folded over the top of the bag, and when stapled to the handle 18, form a more effective means of closure. As shown in Fig. 2, one layer of tab 32 may be folded outwardly as shown, and the other layer folded in the other direction, the two forming a handhold with smooth contact for the fingers, so that the bag 25 may be easily carried without discomfort or injury.

In operating my improved apparatus, the exposed end of the double layer of paper is pulled off the roll and such double layer is drawn forward upon the table 16 until it is under the die 11, when the first handle is cut therefrom. Thereupon the paper is again drawn just far enough forward to remove such handle from the die, and the operation is repeated to form suc-

cessive handles in gang formation, until the outer edge of the first handle abuts against the stop latch 36, so that engagement of the tapered extension 34 upon the underside of the stapler 22 can accurately be made with the slot 28 of the handle adjacent thereto, and also with the slot 35 in the table 16, which slot is positioned to register with and receive such extension. The gang of cut handles so being in operative position, the top of the bag 25 is brought upwardly over the guides 38 in the direction of the stapler so that the edge of said top abuts against the stops 39, while the middle portion of said top is introduced between the layers A and B of the outer handle. The bag and handle being so brought together in proper adjustment, the stapler is then pressed down and the staples 31 affixed as shown in Figs. 1 and 2, whereupon the handle is firmly fastened to the bag and operative for the purposes of my invention, upon such handle being torn from the gang.

To facilitate the ready removal of the outermost handle after it has been stapled to a bag in the manner above described, I prefer to employ the spring latch 36, which is equipped with the spring 42 engaging with shank 41 of said latch within the box 40, secured to the base 7; such latch being so positioned as to readily engage with one of slots 28 adjacent thereto. (See Fig. 1.) Such engagement having been effected after the stapling operation has taken place, the outermost handle may be easily torn off and separated from the gang, the scoring therebetween readily permitting such separation, and the spring latch operating as a stop to prevent the gang being drawn out of operative position beneath the die and stapler. By successive repetitions of the aforesaid modes of operation, further bag handles may be died out and stapled to bags adapted to or suitable therefor, until the entire roll of paper has been consumed.

While I have heretofore shown and described an apparatus in which the die and stapler are preferably rigidly connected and hinged to the table so as to move downwardly and upwardly together in close association, such connection, as is obvious, may be dispensed with by separating the said die and stapler, and hingedly mounting each of said elements so that the same can operate independently in the manner well known in the art; it being desirable, however, where the successive operation of dieing and stapling are required, to have the die and stapler in the same relative positions shown in the drawings.

In making the forms of bag handle shown in Figs. 7 and 8, a die separate and different from that shown in Fig. 1 would be required, although such handle when formed and separated from its gang could readily be stapled to a bag upon my apparatus in the manner hereinbefore described. In fact, if desired, the die shown as forming part of the apparatus shown in Fig. 1 could be dispensed with, and such apparatus used entirely for the purpose of attaching the handle to the bag, the cutting out of the said forms being accomplished prior thereto as a separate operation.

Where in the appended claims a die is referred to, I desire to be understood as including within the meaning of such word adequate and suitable means for cutting out bag handles from a single or a double thickness of material, including knives, perforators or scorers, and other instrumentalities as might be necessary or desirable for such purpose.

My invention may be embodied in other specific forms without departing from the spirit or essential characteristics thereof. The present embodiments of my invention, as hereinbefore delineated and described, are therefore to be considered in all respects illustrative and not restrictive; the scope of my invention being indicated by the appended claims rather than by the foregoing description, and all changes which come within the meaning and range of equivalency of the claims are accordingly intended to be embraced therein.

What I claim and desire to secure by Letters Patent is:

1. In an apparatus for making bag handles, a base, means for cutting out bag handles from double thicknesses of material mounted thereon, and means mounted on said base for fastening said bag handles each to the top of a bag. 15
2. In an apparatus for making bag handles, a base, a die for cutting out bag handles from double thicknesses of material mounted thereon, and a double stapling machine mounted on said base for fastening said bag handles each to the top of a bag. 20
3. In an apparatus for making bag handles, a base, means for mounting and permitting to be unrolled thereon a roll of double thicknesses of sheet material, means secured to said base for cutting out bag handles from said sheet material, and means mounted on said base adjacent thereto for fastening said bag handles each to the top of a bag. 25
4. In an apparatus for making bag handles, a base, means for mounting and permitting to be unrolled thereon a roll of double thicknesses of sheet material, a die secured to said base for cutting out bag handles from said sheet material, and a double stapling machine mounted on said base adjacent to said die for fastening said bag handles each to the top of a bag. 30
5. In an apparatus for making bag handles, a base, means for mounting thereon and permitting to be unrolled upon said base a roll of double layers of sheet material, a die secured to said base for cutting out bag handles from said sheet material when unrolled, a double stapling machine mounted upon said base adjacent to said die for fastening said bag handles each to the top of a bag, and means for guiding said bag top to said stapling machine. 35
6. In an apparatus for making bag handles, a base, means for mounting thereon and permitting to be unrolled upon said base a roll of double layers of sheet material, a die secured to said base for cutting out bag handles in gang formation from said sheet material when unrolled, a double stapling machine mounted upon said base adjacent to said die for fastening said bag handles each to the top of a bag, means for guiding the gang of bag handles to said machine, and means for guiding said bag top to said stapling machine. 40
7. In an apparatus for making bag handles, a base, means for mounting thereon and permitting to be unrolled upon said base a roll of double layers of sheet material, a die secured to said base for cutting out bag handles in gang formation from said sheet material when unrolled, a double stapling machine secured to said die and cooperating therewith, to form and fasten said bag handles each to the top of a bag, means for holding in operative position and guiding said handles to said machine, and means for guiding said bag top to the stapling position. 45
8. In an apparatus for making and securing bag handles, a base, means for cutting out bag handles from double thickness of material mounted thereon, means mounted upon said base for holding open the layers of said bag handles, and means secured to said base for fastening said bag handles each to the closed top of a bag inserted between said layers. 50
9. In an apparatus for making and securing bag handles, a base, a die for cutting out bag handles from double thicknesses of material mounted thereon, means mounted upon said base for holding open the layers of said handles, and a double stapling machine secured to said base for fastening said handles each to the closed top of a bag when inserted between said layers. 55
10. In an apparatus for making and securing paper bag handles, a base, means for mounting thereon and permitting to be manually unrolled thereupon a roll of double layers of paper, a die mounted upon said base for cutting out bag handles in gang formation from said paper when unrolled, said handles when cut being provided with cut out slots for protective handholds and tear out perforations for severance from said gang, a stapling machine secured to said base adjacent to said die for fastening the flaps of said bag handles each to the outside layers of the closed top of a paper bag, means for guiding the gang of bag handles to the said stapling machine, and means for guiding said bag top to the bag handle in stapling position. 60
11. In an apparatus for making and securing bag handles, a base, means for cutting out a bag handle from a single thickness of material mounted thereon, and means mounted on said base for fastening said bag handle to the top of a bag. 65
12. In an apparatus for making and securing bag handles, a base, a die for cutting out a bag handle from a single thickness of sheet material thereon, and a stapling machine mounted upon said base for fastening said bag handle to the top of a bag. 70
13. In an apparatus for making and securing bag handles, a base, means for mounting and permitting to be unrolled thereon a roll of sheet material, means secured to said base for cutting out bag handles from said sheet material, and means mounted on said base adjacent thereto for fastening said bag handles each to the top of a bag. 75

RODERICK S. CLANCY.
